UNITED STATES PATENT OFFICE.

FREDERICK DIEHL, OF ELIZABETH, NEW JERSEY, ASSIGNOR TO THE SINGER MANUFACTURING COMPANY, OF ELIZABETH, NEW JERSEY, A CORPORATION OF NEW JERSEY.

CONTROLLING DEVICE FOR MOTOR-DRIVEN SEWING MACHINES.

Application filed November 11, 1922. Serial No. 600,239.

To all whom it may concern:

Be it known that I, FREDERICK DIEHL, citizen of the United States, residing at Elizabeth, in the county of Union and State of New Jersey, have invented certain new and useful Improvements in Controlling Devices for Motor-Driven Sewing Machines, of which the following is a specification, reference being had therein to the accompanying drawings.

This invention relates to controlling devices for electrically driven sewing machines and has for an object to provide a combined motor-controller and sewing machine braking attachment which may be assembled before being applied to the sewing machine and which may be easily applied as a unitary assembly to an ordinary sewing machine by one not possessed of a high degree of mechanical skill.

Another object of the invention is to provide a combined motor-controller and machine braking attachment which may be assembled independently of the sewing machine or its driving motor and may be subsequently applied as a unit to such machine in such a manner that the brake may operate mechanically directly on the sewing machine balance-wheel while the controller operates electrically in the motor circuit to control the speed of the motor.

Another object of the invention is to provide a sewing machine driving attachment which is inexpensive to manufacture and install and which is efficient in operation.

Still further, the invention has for an object to provide a combined motor-controller and machine braking attachment of compact and simplified construction.

Further objects of the invention will appear from the following description and claims.

In the accompanying drawings, Fig. 1 represents a fragmentary side elevation of a sewing machine to which is applied an attachment embodying the invention. Fig. 2 is a plan view of the attachment. Fig. 3 is a rear end elevation of a sewing machine with the attachment applied thereto.

Fig. 4 is a view of the operating treadle and 50 Fig. 5 is a horizontal section through the attachment.

In the preferred embodiment of the invention, as illustrated, 1 represents a sewing machine table or table-top on which is 55 stationed an ordinary sewing machine or sewing head having a bed 2 and gooseneck 3 in which is journaled the main-shaft 4 to which is connected by the usual thumb-nut operated clutch 5 the balance-wheel 6 60 having a groove for the belt 7. The machine is driven by means of an electric motor 8 which is preferably mounted at the under side of the table-top 1 and includes a motor-shaft 9 carrying a belt-pulley 10 for the 65 belt 7.

The controlling unit preferably comprises the casing 11 having feet 12 formed with holes for screws 13, whereby the casing may be screwed to the upper side of the table-top 70 under the balance-wheel 6. Mounted in the casing 11 is an electric controller element 14 preferably in the form of a rheostat such as disclosed in the patent of H. L. Zabriskie, No. 1,437,629, of December 5, 75 1922; a rheostat of this type being also disclosed in my Patent No. 1,369,407, of February 22, 1921. This rheostat comprises the usual body or support carrying a set of resistor connected contact points 15, the uppermost of which is not connected to the resistance winding and is a dead point. Over the contact points 15 plays the contact arm 16 which is pivotally mounted on the rheostat body at 17. The contact arm 16 has 80 bent outwardly along its side edges the opposed cheek pieces 18 forming between them a channel-way 19 in which is received a roller 20 carried by the lateral arm 21 rigidly connected to a sleeve 22 fixed to the slide-rod 23 which passes vertically through the casing 11 and projects above the latter. The slide-rod 23 is surrounded within the casing 11 by a coil spring 24 disposed between the sleeve 22 and the bottom wall of the casing 11. This spring urges the slide-rod 23 upwardly and yieldingly urges the arm 16 to its "off" position. Screwed on 85 90 95

the threaded upper end of the slide-rod 23 is a stop-nut 25 and lock-nut 26; the former of which is adapted to strike the leather or felt stop washer 27 resting on a boss 27' of 5 the casing 11 through which the rod 23 passes, thus limiting the downward movement of the slide-rod.

The casing 11 is formed with an upstanding post 28 to the bifurcated upper end of 10 which is pivoted at 29 a brake-arm 30 fitted with a brake-shoe 31 adapted to bear upwardly against the periphery of the balance-wheel 6. The brake-arm 30 is formed with a lateral lug 32 in which is screwed 15 the abutment screw 33 the head of which is in engagement with the upper end of the slide-rod 23. The screw 33 is adjustable in the lug 32 and is locked in adjustable position by means of the lock-nut 34. The rheostat 14 is electrically connected, as usual, to the motor circuit by means of the wires 35.

The slide-rod 23 may be connected for manual control by extending a rod 36 from its lower end to the heel-and-toe operated 25 treadle 37. Pressure on the toe or upper edge 38 of the treadle will cause the rod 23 to be pulled downwardly, first relieving the brake and then starting the motor, the speed of which will depend upon the extent to 30 which the toe edge of the treadle is depressed. Pressure upon the heel edge 39 of the treadle will shift the controller to "off" position and forcibly apply the brake. The operator may depend upon the spring 24 to 35 stop the machine instead of pressing on the heel edge of the treadle. A quicker stop may, however, be secured by the operator in assisting the action of the spring 24.

A bobbin-winder 40 of the usual type disclosed for example in my Patent No. 1,455,391, of May 15, 1923, may be mounted on the casing 11 in position for its friction pulley 41 to be shifted into engagement with the rim of the balance-wheel 6. The open 45 side of the casing 11 may be closed by means of a cover-plate 42.

It will be noted that the casing 11 carries the controller 14, brake 30 and bobbin-winder 40. These parts may, therefore, be 50 assembled on or in the casing in correct cooperative relation at their place of manufacture, to be afterward applied to a sewing machine by merely screwing the assembly as a unit to the table-top 1 under 55 the sewing machine balance-wheel 6. By virtue of this provision, it becomes a simple matter to convert an ordinary foot power machine into an electrically driven machine; the services of a skilled mechanic not being 60 required, as no careful relative location or coordination of the parts is required after the device leaves the factory. It is merely necessary to apply the controller as a unitary assembly to the sewing machine. The 65 controller and brake are closely and rigidly

related and are unlikely to get out of adjustment or to require the attention of the operator to keep them in operative condition.

Having thus set forth the nature of the 70 invention, what I claim herein is:

1. A controlling attachment for motor-driven sewing machines comprising a casing, a variable resistance element detachably mounted as a unit within said casing and including a support, a plurality of resistor connected contact points and a shiftable contact arm carried by said support, a brake-lever fulcrumed upon and exteriorly of said casing, and a treadle-operated rod connected at separated points to said shiftable contact arm and brake-lever. 75

2. A controlling attachment for motor-driven sewing machines comprising a casing having spaced top and bottom walls, a slide-rod passing vertically through said casing and having bearings in said top and bottom walls, a variable resistance unit mounted within said casing and including a shiftable contactor operatively connected to the portion of said slide-rod within said casing, and a brake disposed on top of said casing and operatively connected with the exposed upper end of said slide-rod. 80

3. A controlling attachment for motor-driven sewing machines comprising a casing having spaced top and bottom walls, a slide-rod passing vertically through said casing and having bearings in said top and bottom walls, a variable resistance unit mounted within said casing and including a shiftable contactor operatively connected to the portion of said slide-rod within said casing, a brake disposed exteriorly of and above said casing, and an adjustable connection between said brake and the exposed upper end of said slide-rod. 85

4. A controlling attachment for motor-driven sewing machines comprising a casing having spaced top and bottom walls, a slide-rod passing vertically through said casing and having bearings in said top and bottom walls, a variable resistance unit mounted within said casing and including a shiftable contactor operatively connected to the portion of said slide-rod within said casing, and a brake-lever fulcrumed exteriorly of and above said casing and resting by gravity upon the upper end of said rod. 90

5. A controlling attachment for motor-driven sewing machines comprising a casing having vertical side walls, a top wall, and a flat base adapting said casing to be mounted on a sewing machine table-top, a variable resistance unit comprising a supporting body detachably mounted on one side wall of and within said casing and carrying a plurality of resistor connected contact points and a shiftable contact arm adapted to play vertically over said contact points, a treadle- 95

operated rod passing vertically through and
slidably mounted in said casing, the upper
end of said rod projecting through the top
wall of said casing, an operative connection
5 within said casing between said slide-rod
and said shiftable contact-arm, a brake-lever
pivotally mounted on top of said casing, and

an operative connection between said brake-
lever and the exposed upper end of said
slide-rod.

In testimony whereof, I have signed my
name to this specification.

FREDERICK DIEHL.
